CLAIM

The ornamental design for a rechargeable battery, as shown and described.

DESCRIPTION

FIG. 1 is a perspective view of a first embodiment of a rechargeable battery showing my new design; and

FIG. 2 is a front elevational view thereof;

FIG. 3 is a perspective view of the second embodiment of a rechargeable battery showing my new design;

FIG. 4 is a top plan view thereof;

FIG. 5 is a left side elevational view thereof;

FIG. 6 is a front elevational view thereof;

FIG. 7 is a bottom plan view thereof;

FIG. 8 is a right side elevational view thereof; and,

FIG. 9 is a rear elevational view thereof.

The views of the first embodiment which are not shown are the same as those of the second except for the presence to the line extending around the battery along the top, bottom and sides.
